DESIGN FOR A COVER PAPER OR SIMILAR ARTICLE

Jacques Makowsky, Paris, France, assignor to Pinaud Incorporated, New York, N. Y., a corporation of New York

Application July 25, 1938, Serial No. 78,713

Term of patent 14 years

To all whom it may concern:

Be it known that I, Jacques Makowsky, a Russian refugee, residing at Paris 13^e, France, have invented a new, original, and ornamental Design for a Cover Paper or Similar Article, of which the following is a specification, reference being had to the accompanying drawing, forming part thereof.

The figure is a face view of a piece of cover paper showing my design.

The rectangle defined by the parallel lines in the drawing indicates one repeat unit of the design, the line A—A indicating the edge of the paper.

I claim:

The ornamental design for a cover paper or similar article, as shown and described.

JACQUES MAKOWSKY.
